UNITED STATES PATENT OFFICE

160,651

DENTURE BRUSH

Lee Christopher Nugent, Glendale, Calif.

Application October 28, 1949, Serial No. 5,768

Term of patent 14 years

(Cl. D9—2)

To all whom it may concern:

Be it known, that I, Lee Christopher Nugent, a citizen of the United States of America, residing at Glendale, in the county of Los Angeles and State of California, have invented a new, original, and ornamental Design for Denture Brushes, of which the following is a specification, reference being had to the accompanying drawings, forming part thereof.

In the drawing:

Fig. 1 is a perspective view of a denture brush showing my new design.

Fig. 2 is a similar view looking at the opposite side of the brush.

I claim:

The ornamental design for a denture brush, as shown.

LEE CHRISTOPHER NUGENT.
